Patented Sept. 11, 1917.

Inventor.

Edwin C. Peckham

UNITED STATES PATENT OFFICE.

EDWIN C. PECKHAM, OF BROOKLYN, NEW YORK.

HAIR-MEASURER.

1,239,951.

Specification of Letters Patent. Patented Sept. 11, 1917.

Application filed March 14, 1917. Serial No. 154,893.

To all whom it may concern:

Be it known that I, EDWIN C. PECKHAM, a citizen of the United States, and a resident of the city of New York, borough of Brooklyn, in the county of Kings and State of New York, have invented a new and Improved Hair-Measurer, of which the following is a full, clear, and exact description.

My invention relates to a guide for combs, and the object of same is to enable one unskilled in hair cutting to cut or trim hair evenly and expeditiously.

Another object of the invention is to provide a hair measurer which is detachable and which can be quickly attached or detached from a comb.

With the above and other objects in view, the nature of which will more fully appear as the description proceeds, the invention consists in the novel construction, combination and arrangement of the parts as herein fully described, illustrated and claimed.

In the accompanying drawing, forming part of the application, similar characters of reference indicate corresponding parts in all the views, and

Figure 1 is a perspective elevation of a comb provided with a hair measurer embodying my invention;

Fig. 2 is a perspective view of a hair measurer having a flange adapted to be disposed in the direction of the teeth of the comb when the measurer is fitted on to the comb; and

Fig. 3 is a perspective view of a hair measurer in which the flange is adapted to be disposed rearwardly of the teeth of the comb when the measurer is in engagement with the comb.

Referring to the drawings, 4 is a hair measurer which is preferably formed of sheet material, and which is of an elongated form. A longitudinal portion of the hair measurer is bent to form a channel 5 near one of the longitudinal edges of the measurer, the channel 5 corresponding to the back of the comb with which the measurer

is to be used. The straight portion of the flange 6 of the measurer extends at an angle to the teeth of the comb 7, when the channel shaped portion 5 is fitted on the back of the comb 8.

As shown in the drawing, the comb has longitudinal grooves 9 between the back and the teeth of the comb into which the longitudinal edges of the channel portion 5 are adapted to enter, and thereby prevent any lateral displacement of the measurer on the comb. The measurer being formed of sheet material, the channel portion of same is adapted to yield sufficiently so that it can be fitted tightly on to the back of the comb.

In Fig. 2 the measurer 4' is shown with a narrower flange 6' extending from the channel portion 5' at an angle different from that shown in Fig. 1.

In Fig. 3 the flange 6² is larger than the flanges of the measurers in the other figures, and at a different angle with its channel portion 5².

I claim:

1. In combination with a comb having a back of substantially circular cross section and shaped to present a longitudinal groove at each side of said comb between said back and the teeth of the comb, and a hair measurer adapted to detachably embrace said back and engage said groove and having a measuring flange extending therefrom.

2. A hair measurer formed of flat sheet material having a straight flange and a channel portion at an angle to said straight portion, said channel portion adapted to fit the back of a comb so as to present the straight flange portion at an angle to the teeth of the comb.

3. A hair measurer comprising a channel portion adapted to fit the back of a comb and a straight portion extending from one of the longitudinal edges of the channel portion and adapted to be disposed at an angle to the teeth of a comb when the channel portion engages the back of a comb.

EDWIN C. PECKHAM.
